PUMP

Clyde E. Duncan and Frank O. Leeman,
Providence, R. I.

Application July 17, 1933, Serial No. 680,852

1 Claim. (Cl. 103—205)

This invention has reference to pumps and the object of the invention is to provide an organization for pumping fuel oil to range oil burners from a reservoir situated in the basement or any other part of the building, although and as will appear apparent to those skilled in the art the pump can be used for a number of other purposes such as a house pump for drawing water from wells, a service pump at gasoline service stations for drawing gasoline from one tank to another or as a service pump for general use as for example pumping water from flooded cellars.

The invention together with its numerous objects and advantages will be best understood from a study of the following description taken in connection with the accompanying drawings wherein is illustrated a preferred embodiment of the invention.

It is to be understood at the outset that it is in no wise intended to restrict the invention to the precise details of construction, combination and arrangement of elements as herein specifically shown and described, other than may be necessary to meet the requirements of the prior art and scope of the appended claim.

In the drawings:

Figure 1 is an elevational view illustrating the application of the invention.

Figure 2 is a fragmentary sectional view showing the ball valve connection between two sections of the conduit line connecting the reservoir with the pump cylinder, and

Figure 3 is an enlarged view illustrating certain details of construction to be hereinafter more fully referred to.

Referring to the drawings by reference numerals it will be seen that 10 indicates generally a supporting structure including among other parts vertical posts 11, 12, and 13 respectively. Secured on the post 12 at the desired adjustment through the medium of set screws 14 are collars 15 that have pivoted thereto sections of two-part clamps 16 that embrace and are secured about the upper and lower ends of a pump cylinder 17. Mounted for reciprocation within the pump cylinder 17 is a piston 18 having a rod 19 that operates through a gland structure 20 provided at the upper end of the cylinder. At its upper outer end the rod 19 is provided with a laterally directed extremity 21 that is connected through the medium of a pitman rod 22 with a crank pin 23 provided on a fly wheel 24, mounted on a horizontal shaft 25. The shaft 25 is journalled in bearings on the ends of arms 26 integral with a collar 27 suitably mounted on post 11. On the

free end of the shaft 25 is a handle 28 and obviously by rotating the handle 28 reciprocatory movement is imparted to the piston 18.

Suitably mounted on the lower end of the pump cylinder 17 is a frusto-conical head 29 between which and the lower end of the cylinder is clamped a screen 30. The head 29 below the screen 30 provides a valve chamber in which operates a ball check valve 31 that normally engages a seat provided therefor at the inner end of a depending neck integral with the head 29 at its apex.

An inlet nipple 32 connects the inlet neck of the head 29 with the upper end of a conduit pipe section 32. The lower end of the pipe section 32 is provided with a nipple 33 that has its free end threaded into a plug 34 which in turn is threaded into the upper end of a reducer 35. The reducer 35 at its lower end is connected through the medium of an elbow 36 with a pipe section 37 that leads from a suitable outlet provided in the bottom of a storage tank 39 which may be located in the cellar of a building and which may contain fuel oil suitable for range oil burners. The nipple 36 at the end thereof associated with the reducer 35 is formed to provide a seat for a ball check valve and disposed across the upper portion of the reducer 35 is a stop pin 41 which limits the upward movement of the ball 40. This prevents the ball 40 from closing the passage through the plug 34. It will thus be seen that when the pump is in operation the fuel from the tank 39 at each upward stroke of the piston 18 will be drawn from the tank 39 through the pipe sections 37, 32 and associated parts into the bottom of the cylinder while on the down stroke of the piston 18 the oil in the cylinder will be forced therefrom through the medium of means hereinafter more fully referred to into a tank 42. For conducting the liquid from the pump to the tank 42 there is provided at the bottom of the cylinder 17 and above the screen 30 an outlet 43 that is connected by an elbow 44 with a reducer 45. In the upper end of the reducer 45 there is a plug 46 that is connected by a nipple 47 with one end of piping 48, the other end of which piping is connected as at 49 with the top of the tank 42 for emptying into said tank 42. The reducer 45 has operating therein a ball check valve 50 adapted to seat on the inner end of the elbow 44, and a cross pin 51 for limiting the upward movement of the check valve 50 and to prevent said valve from closing the passage through the plug 46.

On one side thereof the tank 42 is provided with suitable cleats 52 adapted to engage in suitable brackets 53 formed integral with clamps 54 that

are secured on the standard 13 as will be clear from a study of Figure 1. To facilitate transportation of the tank 42 the same is provided with a bail or handle 55.

5 The bottom of the tank 42 is connected through the medium of a short pipe section 56 with a reservoir 57 that is also supported from the post 13 by suitable means 58. The reservoir 57 has a removable lid 59 with which is screw threaded 10 engaged the lower end of the pipe section 56. The reservoir 15 in the bottom thereof is provided with an opening into which is screw threaded one end of a pipe 60 that is connected to the burner or the like for supplying the fuel oil to the burner. 15 In said bottom and about the opening therein, the reservoir 57 is provided with a recess into which is snugly fitted a suitable filtering pad 61. For controlling the supply of fuel oil from the tank 42 to the reservoir 57 there is suitably provided in the bottom of the tank 42 a cage 62 in which 20 operates a ball valve 63.

25 Float control means is provided for unseating the valve 63, and such means consists of a shaft 64 supported between opposed walls of the reservoir 57 and having rockable thereon an arm 65. On one end of the arm 65 is a float 66 while the other end of the arm is pivotally connected with an ejector stem 67 that is constrained to shift vertically within the pipe section 56 through the medium of a suitable guide member or bar 68. On 30 its upper end the stem 67 is provided with a head 69 adapted to engage the ball 63 to unseat the ball and thereby permit the contents of the tank 42, or a portion thereof to pass through the pipe 56 and into the reservoir 57. Obviously when the liquid level in the reservoir 57 rises sufficiently to raise the float 66 the arm 65 will be rocked in a clockwise direction moving the stem 67 downwardly and permitting the ball 63 to engage the 35 seat for cutting off the supply of liquid from the tank 42. When the liquid level in the reservoir 57 falls the arm 65 will be rotated in an anti-clockwise direction thus moving the stem 67 up-

wardly to engage the head 69 of the stem with the ball 63 for unseating the latter and permitting a flow of fuel from the tank 42 to the reservoir.

5 The operation of the device is thought apparent to those skilled in the art from the foregoing, but may be briefly explained as follows.

Upon upward movement of the piston 18 a suction is created in the line formed by the pipe sections 32, 37, sufficient to draw fuel from the tank 39, the fuel passing into the head 29. On the downward stroke of the piston 18 pressure on the valves 31, 40 cause these valves to seat and the fuel in the pump will be forced through the pipe connection between the cylinder 17 and the tank 42 into the tank. The tank 42 of course supplies the fuel to the reservoir 57 and the supply of fuel from the tank 42 to the reservoir 57 is of course controlled by the liquid level in the reservoir. From the reservoir 57 the fuel is supplied through the conduit 60 to an oil burner.

10 While we have described the device as being used for lifting fuel oil for consumption in range oil burners, it will be understood that the device could also be put to other uses embodying the 15 lifting of fluid.

20 Having thus described our invention, what we claim as new is:—

25 In a liquid handling apparatus, a frame including a pair of spaced uprights, a vertically arranged cylinder supported by one upright, a piston in the cylinder, a rod connected with the piston and passing through the top of the cylinder and having its upper end bent at right angles toward the other upright, a horizontally arranged 30 shaft supported from the said other upright, a crank disk connected to the inner end of the shaft, a pitman for connecting the crank of the disk with the bent end of the rod, and a handle on the outer end of the shaft for rotating the same. 35
